UNITED STATES PATENT OFFICE.

JOHN NILSEN SELVIK, OF CHICAGO, ILLINOIS, ASSIGNOR TO WESTERN ELECTRIC COMPANY, INCORPORATED, OF NEW YORK, N. Y., A CORPORATION OF NEW YORK.

WIRE-DRAWING MACHINE.

Application filed June 6, 1922, Serial No. 566,384. Renewed October 23, 1926.

This invention relates to improvements in wire drawing machines.

The object of the invention is to provide a wire drawing machine with a novel form of lubricating system and so controlled that lubricant is supplied the drawing mechanism only during the time that such drawing mechanism is in operation. To this end the machine is provided with a capstan, mechanism for driving the capstan, a clutch for connecting the capstan to and from the driving mechanism, a hollow die block arranged above the capstan, together with means for supplying lubricant to the interior of said die block for lubricating the dies in such quantity that it drains onto the capstan for lubricating it, a valve being provided for controlling the lubricant supply, the said valve and capstan clutch mechanism being so connected that the valve is opened and closed as the clutch is engaged and disengaged respectively.

Other objects and advantages of the invention will be set forth in the following description and particularly pointed out in the appended claims.

The accompanying drawings illustrate one embodiment of the invention, in which:

Fig. 1 is a front elevation, parts being broken away, showing a wire drawing machine embodying the features of the invention;

Fig. 2 is an enlarged fragmentary side elevation, partly in section, showing the mechanism for simultaneously stopping and starting the capstan and opening and closing the valve for supplying lubricant to the die block;

Fig. 3 is an enlarged vertical sectional view of that portion of the capstan that is broken away in Fig. 2 and showing in detail the construction of the clutch mounted within the capstan;

Fig. 4 is an enlarged detail view showing the connection between the rod for operating the capstan clutch and the levers for opening and closing the lubricant supply valve, and Fig. 5 is a fragmentary sectional view taken on the lines 5—5 of Fig. 2 showing a front elevation of some of the valve parts.

Referring now to the drawings in detail in which like reference numerals designate similar parts throughout the several views, 10 represents a framework which supports

a compartment 5 of substantially rectangular shape having top, bottom, back, and side walls 11, 12, 13, and 14 respectively. The front of the compartment may be closed by a suitable door or doors (not shown). The wire drawing apparatus is mounted within this compartment and comprises a horizontally disposed shaft 18 upon which is mounted a plurality of integral capstans 17—17 of different diameters. The shaft 18 is driven through suitable gearing and a motor (not shown) carried by the framework and is coupled to and from the capstans through a clutch mechanism hereinafter described. Mounted above the shaft 18 are a plurality of sheaves 19 independently rotatable upon a horizontally disposed shaft 20 suitably supported within the compartment 5. Mounted between the sheaves 19 and capstans 17—17 is a die block 21 carried by a bracket 22 secured to the back wall of the said compartment. For a detailed illustration and description of the sheaves 19 and the driving mechanism for the capstan shaft 18 reference is made to applicant's co-pending application, Serial No. 541,633, filed March 7, 1922. The details of this construction have been omitted from the present application for the sake of simplicity, since a full description of the sheaves and driving mechanism for the capstan shaft 18 is not essential to a complete understanding of the present invention.

The mechanism for coupling the capstans 17 to and disconnecting them from the driving shaft 18 is shown in Figs. 2 and 3 of the drawing, the clutch being illustrated in its operated position. The shaft 18 is in the form of a sleeve which projects through a horizontally and centrally disposed opening made through the capstans 17—17. This sleeve carries adjacent its outer end (Fig. 3) an annular member 70 fast thereto which has secured to it by means of a pin 71 a plurality of clutch disks 72. Alternately mounted between the clutch disks 72 are clutch disks 73 which are secured by a pin 74 to the inner peripheral wall of a cup-shaped opening 75 made in the capstans 17—17. The disks 72 and 73 are movable longitudinally on the pins 71 and 74 respectively, and when pressure is exerted to force the disks together they form a driving connection between the capstans 17—17 and the sleeve 18, as is readily understood. The 110

means for forcing the disks 72 and 73 together comprises a plate 76 which engages the outermost disk, and when the said plate is moved toward the right, into the position shown serves to force the disks together sufficiently to cause them to rotate as a unit. The plate 76 is fastened to one end of a shaft 77 mounted within the sleeve 18. A transverse pin 79 is secured in the shaft 77 and projects through diametrically opposite longitudinal slots 80 cut in the sleeve 18 and engages an annular channel formed in the interior wall of a housing 78 so as to be movable longitudinally with but free to rotate independently of the said housing. Through the medium of the pin 79 and slots 80, the shaft 77 and housing 78 are movable together longitudinally of the sleeve 18. Means (not shown) is provided for preventing the housing from turning but permitting it to move longitudinally of the sleeve 18. Secured to the sides of the housing 78 at diametrically opposite points are pins 81 which receive the bifurcated ends of a forked member 82 which is pivoted at 83 to a link 84. The link 84 has secured to its free end a pin 85 which fits within a slot formed in the upper end of a vertically reciprocable rod 86.

For a more detailed illustration and description of the clutch mechanism per se reference is made to the co-pending application of W. F. Horsford, Serial No. 566,206, filed June 6, 1922.

When it is desired to revolve the capstans 17—17 the rod 86 is moved upwardly, as viewed in Fig. 2, by means of a foot treadle, handle, or other suitable means (not shown). As the rod 86 moves upward the housing 78 is moved to the right longitudinally of the shaft 18 through the medium of the link 84 and forked member 82 into the position shown in Figs. 2 and 3. The housing 78 carries with it, the shaft 77, through the medium of pin 79, causing the plate 76 carried by the shaft to exert sufficient pressure on the disks 72 and 73 to cause them to form a driving connection between the sleeve 18 and capstans 17. When the means for raising the rod 86 is released, the said rod is restored to its initial position and the housing 78 and shaft 77 moved toward the left, as viewed in Fig. 2, by means of energy stored in a compressed spring 87, which has one of its ends in engagement with the shaft 77 and its other end against a plug 88 screwed within the end of the sleeve 18. The housing 78 in moving toward the left, as above described, engages a brake member 89 carried thereby against an annular member 90 secured to the capstan and serves to stop the rotation thereof.

Referring now to the lubricating system, the die block 21 comprises a hollow, horizontally disposed body portion 22 having se-

cured thereto shelves 23 and 24, each of which is adapted to support a series of dies thereon (not shown). One end of the body portion 22 is provided with an opening 27 (Fig. 2) through which projects a valve casing 28 provided with a series of openings 29 which communicate with the interior of the body portion 22. Suitably supported within the valve casing 28 is a valve 30 which is normally held on its seat by a compression spring 31. In communication with the valve 30 and suitably supported is a pipe 32 connected by an elbow 33 with a vertically disposed pipe 34 which is connected to the outlet port of a pump 35. The intake port of the pump has connected thereto a pipe 36 which is suitably supported within an opening 37 formed in the bottom wall 12 of the compartment 5. Disposed above the bottom wall 12 and parallel therewith is a screen 38, the purpose of which will be hereinafter described.

When the capstans 17 are set in motion by raising the rod 86, as previously described, the valve 30 is simultaneously opened by means of an arm 39 which is turned counterclockwise about its pivot 91 to move the valve 40 off of its seat. The arm 39 is given the movement just described by means of a plunger 92 reciprocably mounted within a bearing 93 carried by the back wall 13 of the compartment 5, one end of the said rod being in engagement with the arm 39 and its other end having a pin and slot connection with a bell-crank lever 94 pivoted at 95 to a bracket 96 suitably supported by the framework of the machine. Pivoted to the bell-crank lever 94 is one end of a link 96, the lower end of which is pivoted at 97 to an arm 98 pivotally mounted upon a stud 99 carried by the framework of the machine. The arm 98 is provided with a projection 100 which fits within a recess 101 formed in the rod 86 (Fig. 4).

The pump 35 serves to draw lubricant placed in the compartment 5 and lift it into the interior of the body portion 22 of the die block, from which it is forced on top of the dies supported on the shelves 23 and 24 through a series of openings 23' and 24' respectively. For a detailed description and disclosure of the construction of the die block reference is made to the co-pending application of F. S. Kochendorfer, Serial No. 566,285, filed June 6, 1922. The lubricant is supplied to the dies in such quantities that it overflows the shelves 23 and 24 and drops onto the capstans 17 mounted beneath the die block and serves to thoroughly lubricate said capstans. Excess lubricant supplied to the capstans drains therefrom through the screen 38 onto the bottom 12 of the compartment, from which it is again lifted into the interior of the die block by the pump 35.

Due to the construction of the lubricating system just described and the operative connection between the clutch for stopping and starting the capstan and the valve for controlling the supply of lubricant to the die block, the wire drawing apparatus is only lubricated during such times as it is in operation, and whenever the capstan is stopped, the lubricant is cut off. Since the flow of lubricant is controlled automatically by the stopping and starting of the capstan, whenever the capstan is in operation sufficient lubricant is insured, the supply of which is not dependent upon the discretion of the operator, and when the capstan is idle no lubricant is supplied the dies or capstan, which might interfere with the adjustment of the apparatus or stringing of the machine.

A supply of wire to be reduced in diameter is carried by a supply spool 50 suitably mounted at the front of the machine. The wire is guided from the supply spool over and under pulleys 51 and 52 respectively and then over the rear sheave 19 and through the first reducing die carried by the die shelf 23. The wire is then wound once around the capstan 17 of smallest diameter, after which it is passed upward and over the next sheave 19 and through the next reducing die carried by the die shelf 24. The wire is then wound around the next capstan and then again over the next sheave 19 and through the next reducing die, etc., etc., until it is finally drawn down to the desired diameter by the last reducing die. From the final reducing die the drawn wire passes around the capstan 17 of largest diameter and is guided by a pulley 57 rotatably mounted on a stationary arm 58 adjustably positioned on the shaft 20 to a pulley 59 carried by a lever 60. From the pulley 59 the wire is led to a take-up spool 61 driven by suitable mechanism (not shown).

What is claimed is:

1. In a wire drawing machine, a capstan, means for rotating said capstan, a die block located above the capstan, means for supplying lubricant to said die block in such quantity that it drains onto said capstan for lubricating it, a valve for controlling the lubricant supply, and means associated with said valve and capstan whereby the valve is opened and closed when the capstan is rotating and idle respectively.

2. In a wire drawing machine, a capstan, a driving mechanism therefor, means for operatively connecting and disconnecting the capstan to and from the driving mechanism, a die block located above the capstan, means for supplying lubricant to said die block in such quantity that it drains onto said capstan for lubricating it, a valve for controlling the said lubricant supply, and means connecting said valve and said capstan connecting means whereby the valve is

opened and closed as the capstan is connected to and disconnected from the driving means respectively.

3. In a wire drawing machine, a capstan, a driving mechanism therefor, a clutch for operatively connecting and disconnecting the capstan to and from the driving mechanism a die block located above the capstan, means for supplying lubricant to said die block in such quantity that it drains onto the capstan for lubricating it, a valve for controlling said lubricant supply, and means connecting said valve to said clutch mechanism whereby the valve is opened and closed as the clutch is engaged and disengaged respectively.

4. In a wire drawing machine, a capstan, a driving mechanism therefor, a clutch for operatively connecting and disconnecting the capstan to and from the driving mechanism, a hollow die block located above the capstan and having a plurality of openings therein, means for supplying lubricant in such quantity to the die block and through said openings for lubricating the dies that it is drained onto the capstan for lubricating it, a valve for controlling the said lubricant supply, and means connecting said valve with said clutch whereby the valve is opened and closed as the clutch is engaged and disengaged respectively.

5. In a wire drawing machine, two shafts, a series of sheaves mounted on one of said shafts, a capstan mounted on the other shaft, a hollow die block having a plurality of openings therein, a drive shaft, a clutch for operatively connecting and disconnecting the capstan to and from the drive shaft, means for supplying lubricant to said die block and through said openings for lubricating the dies, a valve for controlling the said lubricant supply, and means connecting said valve with said clutch mechanism whereby the valve is opened and closed as the clutch is engaged and disengaged respectively.

6. In a wire drawing machine, two longitudinal shafts one located above the other, a series of sheaves independently mounted on the upper shaft, a cone capstan mounted on the lower shaft, means for driving said capstan shaft, a clutch for operatively connecting and disconnecting the capstan to and from the capstan shaft, a hollow die block having a plurality of openings therein, said die block mounted between the sheaves and capstan, means for supplying lubricant to the die block and through said openings for lubricating the dies, a valve for controlling the said lubricant supply, and means connecting said valve with said clutch whereby the valve is opened and closed as the clutch is engaged and disengaged respectively.

7. In a wire drawing apparatus, a pair of

horizontal shafts, a series of sheaves mounted on one of said shafts, a stepped capstan mounted on the other shaft, a hollow die block having a plurality of openings, means for driving said capstan, a clutch for engaging and disengaging said capstan to and from the capstan shaft, means for supplying lubricant to the interior of said die block and through said openings whereby said lubricant is fed to the dies, said die block arranged between the sheaves and capstan whereby excess lubricant supplied the dies is deposited on the capstan for lubricating it, a valve for controlling the supply of lubricant to the die block, and means connecting said valve with said clutch whereby said valve is opened and closed as the clutch is engaged and disengaged respectively.

8. In a wire drawing machine, a die, means for drawing a wire therethrough, means for controlling the operation thereof, means for supplying lubricant to the die in such quantities that it drains onto the drawing means, and means associated with the controlling means for controlling the means for supplying lubricant to the die.

9. In a wire drawing machine, a die, means for drawing a wire therethrough, means for controlling the operation thereof, means for supplying lubricant to the die in such quantity that it drains onto the drawing means, and means associated with the controlling means and including a valve for controlling the lubricant supply.

35 10. In a wire drawing machine, a die, means for drawing a wire therethrough, means for supplying lubricant to the die in such quantity that it drains onto the drawing means, a valve for controlling the lubricant supply, and means associated with the valve and the drawing means whereby the valve is open and closed when the drawing means is operating and idle, respectively.

11. In a wire drawing machine, a die, means for drawing a wire therethrough, means for supplying lubricant to the die in such quantity that it drains onto the drawing means, a valve for controlling the lubricant supply and means associated with the drawing means for maintaining the valve open while the drawing means is operating.

12. In a wire drawing machine, a die, means for drawing a wire therethrough, means for supplying lubricant to the die in such quantity that it drains onto the drawing means, a valve for controlling the lubricant supply and means associated with the

drawing means for maintaining the valve closed while the drawing means is idle.

13. In a wire drawing machine, a die, means for drawing a wire therethrough, means for driving the drawing means, means for supplying lubricant to the die in such quantity that it drains onto the drawing means, a valve for controlling the lubricant supply and means interconnecting the valve and the drawing mechanism whereby the valve is maintained open while the drawing means is operating and closed while the drawing means is idle.

14. In a wire drawing machine, a die, means for drawing a wire therethrough, means for driving the drawing means, a clutch mechanism having a plurality of engageable members for connecting the drawing means to and disconnecting it from the driving means, means for supplying lubricant to the die in such quantity that it drains onto the drawing means, a valve for controlling the lubricant supply and means interconnecting the valve and the drawing mechanism for closing the valve as the clutch members disengage.

15. In a wire drawing machine, a die, means for drawing a wire therethrough, means for driving the drawing means and clutch mechanism having a plurality of engageable members for connecting the drawing means to and disconnecting it from the driving means, means for supplying lubricant to the die in such quantity that it drains onto the drawing means, a valve for controlling the lubricant supply, and means interconnecting the valve and the drawing mechanism for closing the valve as the clutch members disengage.

16. In a wire drawing machine, a die, means for drawing a wire therethrough, means for driving the drawing means and clutch mechanism having a plurality of engageable members for connecting the drawing means to and disconnecting it from the driving means, means for supplying lubricant to the die in such quantity that it drains onto the drawing means, a valve for controlling the lubricant supply and means interconnecting the valve and the drawing mechanism for opening the valve as the clutch members engage and closing it as the clutch members disengage.

In witness whereof, I hereunto subscribe my name this 31st day of May A. D., 1922.

JOHN NILSEN SELVIG.
